CLAIM

The ornamental design for a vibrato bridge for stringed
musical instruments, as shown and described.

DESCRIPTION

FIG. 1 is a front, top and left side perspective view of a
vibrato bridge for stringed musical instruments showing
my new design;

FIG. 2 is a rear, bottom and left side perspective view;

FIG. 3 is a top plan view;

FIG. 4 is a right side elevational view;

FIG. 5 is a rear elevational view.

The broken line structure is environmental and is not
part of the claimed design.
